GAS MIXER

Charles W. Philip, San Francisco, Calif., assignor
to Philip Manufacturing Company, Oakland,
Calif., a corporation of California

Application March 16, 1933, Serial No. 661,030

2 Claims. (Cl. 48—180)

This invention relates particularly to a liquid fuel gasifier for internal combustion engines.

An object of the invention is to provide a liquid fuel gasifying device between the carburetor and the intake manifold of a conventional internal combustion engine, to convert all of the relatively heavy liquid fuel particles into gas so that the same will be readily combustible when carried into the engine cylinders.

10 A further object of the invention is to provide a liquid fuel gasifying device through which the gaseous mixture from an engine carburetor passes to increase the combustibility of the said mixture before entry thereof into the intake manifold of the machine. The highly volatile portions of the fuel will readily mix with the air stream flowing into the intake manifold, whereas the heavier and less volatile portions of the fuel do not form a readily combustible gaseous mixture. 15 My gasifier subjects the less volatile portions of the fuel to a heat treatment so that the same will be readily combustible when introduced into the engine cylinders.

20 A still further object of the invention is to provide a liquid fuel gasifying device to be heated by the exhaust gases of the engine, and the amount of exhaust gases that are by-passed into and through the heating device is in direct inverse ratio with the volume of gaseous fuel that passes 25 through the gasifier to the engine cylinders.

25 Other objects and advantages are to provide a liquid fuel gasifier for internal combustion engines that will be superior in point of simplicity, inexpensiveness of construction, positiveness of 30 operation, and facility and convenience in use and general efficiency.

35 In this specification and the annexed drawings, the invention is illustrated in the form considered 40 to be the best, but it is to be understood that the invention is not limited to such form, because it may be embodied in other forms; and it is also to be understood that in and by the claims following the description, it is desired to cover the 45 invention in whatsoever form it may be embodied.

45 In the accompanying drawings:

Fig. 1 represents a side elevation of an internal combustion engine having a liquid fuel gasifying device arranged thereon between the carburetor 50 and intake manifold.

Fig. 2 is an enlarged vertical section taken through a liquid fuel gasifying device constructed in accordance with my invention.

55 Fig. 3 is a plan view taken through Fig. 2, on the line 3—3.

Fig. 4 is a plan view of the gasifier showing the interior of the outer shell.

The invention herein described is designed primarily to preheat the gases or vapors of low grade hydrocarbon fuels and to make the same readily combustible when used in conventional internal combustion engines. All liquid fuels of mixed high and low grade or gravity have certain portions thereof which are highly volatile and which are readily usable for combustion purposes. 5 Higher grade fuels promote combustion more readily than lower grade fuels, and it is not necessary to preheat higher gravity fuels for combustion purposes. My invention is designed primarily to accomplish the breaking up of all low 10 gravity fuels of proper character, into combustible gases or vapors, to accomplish the same efficient operation in usage that results from the use of higher gravity fuels.

In detail the construction illustrated in the 20 drawings includes an internal combustion engine designated by the numeral 1, and having an intake manifold 2 connected with the respective engine cylinders, as well as an exhaust pipe 3 leading from said cylinders. A carburetor 4 is 25 arranged adjacent the intake manifold 2, and between the said carburetor and intake manifold, I have interposed my fuel gasifying device 5.

The gasifier has its lower end secured to a 30 union 6 on the intake manifold, while the upper end of the gasifier is bolted or otherwise secured to the under side of the carburetor 4. The carburetor 4 may be of any of the well known types of carburetors, and said carburetor has a butterfly valve 7 therein, which regulates the amount 35 of air which passes through the carburetor to carry the fuel vapors into the engine cylinders. The valve 7 is manipulated through a connection 40 to either the hand or foot accelerator rod 8 of the engine control.

The gasifier 5 consists of an ovoid body 9 which is of larger diameter at its upper end than at the lower end. The upper end of the body 9 is provided with a flanged surface with circumferentially spaced bolt holes therearound for securing the cover or head 10 thereto. The lower or bottom end of the body 9 is provided with a circumferentially shouldered portion 11 therein, to form a seat for the exterior of the base end 45 of the inner casing 12, said inner casing having an annular shoulder 13 at the bottom thereof which rests on the seat 11, and a flange 14 at the upper end thereof which lies flush and in planar alignment with the upper end of the body 9, and 50 55

seats in circumferential contact with the interior of the upper end thereof. The inner casing 12 contacts the outer body 9 at its lower and upper ends 13 and 14 respectively, and along the line of a vertical baffle 15 which extends between said parts 13 and 14.

A plurality of fins or webs 16 are provided around the exterior of the inner casing 12 to absorb heat from the gases of combustion which pass through the space between the outer body and the inner casing. The outer edges of said webs or fins do not contact the inner face of the outer body. The body 9 is provided with an inlet port 17, at the upper end thereof, on one side of the baffle 15, to which a by-pass pipe 18 is bolted, which pipe communicates with the exhaust manifold 3, and at its lower end the body 9 is provided with an outlet port 19 on the other side of the baffle 15, which outlet port 19 connects through a by-pass manifold 20 to the exhaust pipe 3, see Fig. 4. A valve 21 is provided in the exhaust pipe between the by-pass manifold 18 and the return by-pass 20, and said valve is operated by a link 22 in synchronism with the fuel throttle 7.

In order to divert the exhaust gases of the exhaust pipe into the gasifier, the valve 21 is placed across the exhaust pipe 3, thus compelling the gas therein to flow through the by-pass pipe 18 into and completely around the gasifier before it can discharge outwardly through the return by-pass 20 into the exhaust manifold 3 on the other side of the control valve 21.

Where the engine operates at a relatively slow speed, I have found that a relatively higher proportion of exhaust gases should be passed through the manifold than when the engine is operating at higher speeds. The upper side of the body 9 and casing 12 is closed by a cover 10, the interior of which is provided with a stream-line deflector 23 therein. The deflector 23 is arranged centrally within the opening through the cover 10, being supported therein by spiral spiders or vanes 24.

The mixture of liquid fuel and air from the carburetor 4 which enters the cover 10 is given a whirling impetus by the vanes 24 so that the heavier particles of liquid fuel will be thrown outwardly into contact with the heated walls of the inner casing 12 to thereby vaporize said fuel particles and make the same readily combustible.

The inner contour of the cover 10 and the casing 12 is so designed with relation to the deflector 23 and vanes 24 that the air flow therethrough will reach a point of maximum efficiency, and there will be no air pockets or dead spaces which would tend to decrease the act of gasifying the fuel vapors. The diameter of the deflector, as well as the length thereof, and the position which said deflector occupies in the cover and the casing, insures that all of the heavier unvaporized portions of the fuel will be thrown into contact with the heated walls of the gasifier, and will be converted into a gaseous combustible mixture prior to entry into the intake manifold.

The valve 21 in the exhaust pipe 3 is so positioned that at the commencement of the engine operation, and at such other periods of operation of the engine when the same is idling or running at slow speeds, that practically all of the exhaust gases from the engine will be passed through the double wall space of the gasifier, whereby the maximum amount of heat will be conducted to the inner casing 12 thereof. As the engine speed would increase, the valve 21 would automatically

open with the throttle 7 to by-pass a smaller volume of the exhaust gases into the gasifier. Both the carburetor butterfly valve 7 and the exhaust valve 21 operate simultaneously in relation to each other and in relation to the speed of operation of the engine, both valves being connected by the rods 8 and 22 to the accelerator pedal, not shown.

My gasifier does not heat the carbureted mixture of air and fuel in its entirety but heats only the heavier portions of the fuel thrown outward by centrifugal force. The air containing the higher volatile gases following centripetal lines passes into the engine cylinders in a relatively cool condition. The gasifier does not heat the fuel mixture to a point of hydrocarbon decomposition where the same would be broken down to form carbon and the heat units in the fuel lowered. The central deflector tends to throw the heavier particles of liquid fuel into contact with the heated inner wall of the gasifier, whereby the same are converted into vapor, and proceed in the vapor form into the engine cylinders with the proper amount of air for efficient combustion, said air being heated only to a degree to prevent condensation of the fuel in the intake manifold, and to not reduce the volumetric efficiency thereof.

With my gasifier it is possible to use cheap and low grade liquid hydrocarbon fuels, and to obtain the same efficient operation of an engine as though higher gravity fuels were used. In using the lower gravity fuels it is sometimes desirable to inject a small quantity of water to be carried by the air and fuel mixture into and through the gasifier, said water being converted into steam. The steam thus enters the engine cylinder as a part of the fuel charge and thereby increases the efficiency of the power of explosion of each fuel charge. The addition of water to the fuel mixture tends to eliminate the "knock" or "ping" which sometimes occurs where low gravity fuels are used in operation.

The interior of the casing 12, as well as the interior of the body 9, has the shape of an ellipsoid or conoid. I have found it desirable to make the interior of the casing circular on every horizontal plane throughout its length and elliptical on every vertical plane throughout its length. The inner contour of the casing, including the cover and the lower portion thereof, is substantially "egg-shaped" on the vertical axis. The deflector 23 is arranged co-axially within the casing and is of ellipsoid shape. The shape and position of the deflector is such in relation to the interior of the casing that it effects an increase in temperature of the carbureted mixture of air and fuel passing thru the casing without diminishing the rate of flow of the same therethrough. The facing surfaces of the deflector and the casing are stream-lined to cooperate with and to present a minimum of resistance to the passage of the carbureted mixture of air and fuel through the casing.

Having thus described this invention, what I claim and desire to secure by Letters Patent is:

1. In a gas mixer for an engine which comprises an outer pot-like casing having an outlet port in its bottom for vapor, a cover fitting over said casing having an inlet port for a mixture of liquid fuel and air, an open-top pot spaced within the outer pot and seated at its opposite ends respectively between the outer pot and said cover and having a port in its bottom matching said outlet port, said cover overhanging the space

between the two pots and formed internally to substantially match and continue the inner walls of the inner pot in a converging manner to said inlet port, fins extending from said inner pot, means for circulating hot gas between said pots to cause heating of said fins and pot, spiral fan-like blades carried by said lid in the path of the incoming mixture of liquid fuel and air, and an ellipsoidal deflector supported centrally of said blades.

2. In a gas mixer for an engine which comprises an outer pot-like casing having an outlet port in its bottom for vapor, a cover fitting over said casing having an inlet port for a mixture of liquid fuel and air, an open-top inner pot spaced within

the outer pot and seated at its opposite ends respectively between the outer pot and said cover and having a port in its bottom matching said outlet port, said cover overhanging the space between the two pots and formed internally to substantially match and continue the inner walls of the inner pot in a converging manner to said inlet port, fins extending from said inner pot, means for circulating hot gas between said pots to cause heating of said fins and pot, spiral fan-like blades carried by said lid in the path of the incoming mixture of liquid fuel and air, and a deflector supported centrally of said blades.
